US00D670309S

(12) **United States Design Patent**
Vance et al.

(10) **Patent No.:** **US D670,309 S**
(45) **Date of Patent:** **** Nov. 6, 2012**

(54) **PORTION OF A DISPLAY SCREEN WITH A
USER INTERFACE**

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter Macleod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US)

(73) Assignee: **T-Mobile USA, Inc.**, Bellevue, WA (US)

(**) Term: **14 Years**

(21) Appl. No.: **29/389,939**

(22) Filed: **Apr. 18, 2011**

Related U.S. Application Data

(63) Continuation of application No. 29/334,518, filed on Mar. 27, 2009, now Pat. No. Des. 636,403.

(51) **LOC (9) Cl. 32-00**

(52) **U.S. Cl. D14/486**

(57) **CLAIM**

The ornamental design for a portion of a display screen with a user interface, as shown and described.

DESCRIPTION

THE FIGURE is a front view of portion of a display screen with a user interface showing the claimed design.

The portions of the user interface illustrated in broken lines form no part of the claimed design. The outer edge of the portion of the display screen is understood to be congruent with the outer edge of the user interface.
